UNITED STATES PATENT OFFICE.

FERDINAND G. SPINDLER, OF NEW YORK, N. Y., ASSIGNOR TO ALFRED TRAEGER, OF WEEHAWKEN, NEW JERSEY.

COLORIMETER.

Specification of Letters Patent. Patented Sept. 21, 1920.

1,353,500.

Application filed August 4, 1919. Serial No. 315,260.

To all whom it may concern:

Be it known that I, FERDINAND G. SPINDLER, a subject of the Emperor of Germany, and residing at 431 West 214th street, in the city and State of New York, have invented certain new and useful Improvements in Colorimeters, of which the following is a specification.

My invention relates to colorimeters, and more particularly to that type where a liquid to be tested may be compared with a liquid of standard color by observing both at the same time through a microscope.

In this type of colorimeters there has been great loss of time caused by the necessity of constantly adjusting and readjusting the perpendicular position of the two containers holding the liquids to be compared. This difficulty is entirely overcome in my device, which makes it possible for the person using it to change the perpendicular position of either container while observing the same through the microscope.

Referring to the drawings, Figure 1 is a perspective of my colorimeter; Fig. 2 is a front elevation of my colorimeter, with the upper portion in cross section and the cover removed; Fig. 3 is a side sectional view of Fig. 2 on the line 3-3; Fig. 4 is a top plan sectional view of Fig. 2 on the line 4-4; Fig. 5 is a rear elevation of my colorimeter with the cover removed; Fig. 6 is a bottom plan view of the mirror; Fig. 7 is a perspective of one of the containers with a portion broken away; Fig. 8 is a top plan view of one of the platforms, and Fig. 9 is a side view of the same.

In the drawings 10 is a base to which is rigidly secured a perpendicular support 11. At 12 a bracket 13 is rigidly secured to the top edge of the support 11, and a circular flange 14 cut out of the bracket 13 is adapted to receive a microscope 15 of the usual two lens construction. A hole 16 is cut through the bracket 13 to permit the light to pass through into the microscope, and also to permit the operator to look through. A prism support 17 is rigidly secured to the bracket 13 and cap members 18 at each end of said support 17 are adapted to be readily removed by removing screws 20 so that glass prisms 19 can be inserted or taken out and cleaned. Support 17 has downturned circular flanges 21 into which glass plungers 22 having bottoms 22^a fused to tubular portions 22^b and having metal

flanges 23 are adapted to be fastened by means of screws 24.

Two guide members 25 are secured to the perpendicular support 11 by means of screws 26, and they are cut in on the sides, so as to be narrower at the sides nearer the support 11, so that platforms 27 will fit over the same at the open ends 28 and slide thereon. The platforms 27 also have holes 29 cut through them so that light from below may pass up through, and the operator look through them. Grooves are cut around the edges of the holes 29 so as to form flanges 30 on which transparent containers 31 are adapted to be placed. Containers 31 have separate bottoms 32 secured thereto by fusing or otherwise, same as plungers 22, so that the exact thickness and plane surface of the bottoms can be more perfectly regulated. The platforms 27 are slotted at 33 so as to permit tightening of the sides of the opening 28 on the slides 25 which can be effected by means of the adjustment screws 35. Indicators 34 are rigidly secured to the platforms 27 so that they project through slots 36 in the support 11 and indicate the perpendicular positions of the platforms 27 on a scale 37 which is rigidly secured to the back of the support 11.

Bell crank levers 38 having handles 41 are pivoted in the support 11 below the lower ends of the slides 25 on shafts 39, and are connected to the platforms 27 by means of the links 40 which are connected so that they turn freely at each end. The bell crank levers 38 have long levers 42 rigidly secured to the shafts 39 by means of set screws 43 and short levers 44 rigidly secured to the shafts 39.

A mirror 45 is mounted in the support 11 on a T-shaft 46 by means of a nut 47 and a spring washer 48 below the shafts 39, so that it can be tilted as desired at either end. The mirror 45 is also supported by the bearings 49 on the head of the T-shaft 46 so that it can be tilted down or up on its side edge.

A cover 50 is pivoted by means of pivot screws 51 to the side of the support 11, so that when closed it will shut out all light from the containers 31 and plungers 22, except that thrown up from the mirror 45. The cover 50 is hinged at 52 so that it can be partly opened when desired.

In using my colorimeter a solution of known color density is placed in one of the

containers, and the platform on which said container rests is raised by pulling up on the handle 41 of the lever 38 until the plunger 22 is at the required depth in the 5 solution as indicated by the indicator 34 on the scale 37.

The solution to be tested is then placed in the other container and raised in the same way until the color of both solutions is the 10 same to the eye of the operator. In order to get this container at the proper position to obtain the same color on each half of the field of vision of the operator's eye it may be necessary to raise and lower this second 15 container several times until the color is exactly the same, and this the operator can do with one hand while he is observing the effect through the microscope. As soon as both halves of the field of vision of the 20 operator's eye show the same color so that it appears like one field of vision then the reading of the second indicator can be taken on the scale 37, and this will give the color density of the solution being tested.

25 The mirror 45 should be adjusted before making a test so that the light is reflected directly therefrom into the microscope, as the operator looks through the same and in so doing the light passes through the holes 30 29, containers 31 and the solution therein, the plungers 22, prisms 19 into the lenses of the microscope 15. The cover 50 should be in the closed position during the test.

What I claim is:

35 1. In a colorimeter, the combination with a support, of undercut guideways on the

front face of the support, platforms movable along the support and having container-receiving sockets and rear seats that slidably interfit with the guideways, said platforms being slotted from the sockets to the seats, means for adjusting the platforms, and optical mechanism mounted on the support above the platform for observing materials supported by said platforms. 40 45

2. In a colorimeter, the combination with a support, of independently adjustable container carriers mounted on the support, optical mechanisms mounted on the support for observing materials in the containers 50 placed on the carriers, and a hood for wholly or partly inclosing the containers mounted on the carriers, said hood being hingedly mounted on the support at one side of the carriers and comprising hingedly connected 55 walls.

3. In a colorimeter, the combination with a base, of a standard mounted thereupon, dovetailed guideways on the front side of the standard, platforms having dovetail 60 sockets that slidably receive the guideways, rock shafts journaled in the lower portion of the standard and having crank arms linked to the platforms, optical mechanism mounted on the upper end of the standard 65 for observing materials carried by the platforms, and a hood for partly or wholly inclosing the platforms and comprising hingedly connected walls, one of which is hinged to one side of the standard. 70

In testimony whereof I affix my signature.
FERDINAND G. SPINDLER.
